US00D765139S

(12) United States Design Patent (10) Patent No.: US D765,139 S
(45) Date of Patent: * Aug. 30, 2016

(54) PORTION OF A DISPLAY SCREEN WITH GRAPHICAL USER INTERFACE

(71) Applicant: Tencent Technology (Shenzhen) Company Limited, Shenzhen, Guangdong (CN)

(72) Inventor: Xiao Hu, Guangdong (CN)

(73) Assignee: Tencent Technology (Shenzhen) Company Limited (CN)

() Term: 14 Years

(21) Appl. No.: 29/477,642

(22) Filed: Dec. 24, 2013

(51) LOC (10) Cl. 14-04

(52) U.S. Cl. USPC D14/494

(58) Field of Classification Search

USPC D14/485-495
CPC ... G06T 13/80; G06T 15/02; H04N 1/00424;
G06F 3/04817; G06F 3/0481
